SHEET MATERIAL DISPENSER

Henry R. Johannes, Macungah, Pa., assignor to Caloric Corporation, Topton, Pa., a corporation of Pennsylvania

Filed Feb. 15, 1962, Ser. No. 68,838

Term of patent 14 years

(Cl. D52—2)

Fig. 2.

Fig. 1.

Fig. 3.

FIG. 1 is a front elevational view of a sheet material dispenser embodying my new design.

FIG. 2 is a top plan view of the same.

FIG. 3 is an end elevational view of the same.

The undisclosed end of the dispenser is substantially the same in appearance as the end shown, and the rear is plain. It is to be understood that the ornamentation shown on the right side panel in FIG. 1 is continued throughout that portion of the panel.

I claim:

The ornamental design for a sheet material dispenser, as shown and described.
